INVENTOR.

R. E. Wright

UNITED STATES PATENT OFFICE.

RICHARD ERNEST WRIGHT, OF CAPE TOWN, CAPE OF GOOD HOPE, SOUTH AFRICA.

PENCIL SHARPENER.

Application filed August 13, 1927, Serial No. 212,769, and in Great Britain September 21, 1926.

This invention relates to an improved type of pencil sharpener of the kind in which a safety razor blade of wafer type is employed as the sharpening blade.

5 Generally in this kind of pencil sharpener the blade is clamped or secured on a base having a holder such as a slotted conical tube for the reception of the end of the pencil and sharpening is effected by rotating the pencil 10 against the edge of the blade. Sometimes the blades have been mounted in a pencil sharpening machine so as to revolve with respect to the pencil.

According to this invention, the sharpener 15 comprises a shaped base adapted for the clamping thereto of a safety razor blade in such angular relation to a guide on the base that the pencil may be sharpened by drawing it over the base in engagement with the 20 guide. The base is adapted for supporting the blade against vertical pressure without interfering with the cutting operation and is suitably provided with shoulders for determining the depth of the cut and with side 25 walls for guiding the pencil into gradual contact with the edge of the blade. The blade is secured by a top plate which is of such a construction as to hold the blade rigidly without interfering with the cutting operation and 30 the mounting and fixing means suitably are so constructed and disposed as to enable the pencil to be drawn gradually against the fine edge of the blade to produce a distribution and regulation of the cutting strains suitable 35 for enabling these strains to be withstood by the blade.

The invention is illustrated in the accompanying drawing in which:—

Figure 1 is a plan of the sharpener completely assembled.

Figure 2 is a longitudinal section, along the line 2—2 on Figure 1.

Figure 3 is a side elevation of the sharpener.

45 Figure 4 is an end view of the sharpener.

Figure 5 is a plan of the sharpener with top plate and clamping bolt removed.

Figure 6 is a plan of the base of the sharpener with the top plate, clamping bolt, and blade removed.

In the above figures A is the base made of brass or other suitable metal shaped as shown to allow a space under the edge of the blade, and having tapering shoulders B of the form 55 and in the position shown, along which the

end of the pencil is drawn in the process of sharpening.

The base A has two bulges C over which the holes in a safety razor blade can fit, and which correspond with similarly placed depressions in the top plate F. D is a hole through the base A, through which the clamping bolt G can pass. E is a safety razor blade of the wafer type which fits over the bulges C. The metal top plate F which holds the razor blade 60 in position on the base A, has a hole in its centre through which the clamping bolt G passes, and on this clamping bolt is screwed a nut H for clamping all the parts rigidly together.

70 The device is operated as follows:—

The end of the pencil is drawn along one or the other of the shoulders B, the outer side wall K or K' of the base forcing it gradually against the cutting edge of the obliquely disposed blade which removes a shaving off 75 the pencil. The shoulder B determines the depth of the cut and as the pencil is only gradually forced by the side wall against the edge of the blade, owing to the latter being obliquely mounted with respect to the side 80 wall, it will be seen that there is a gradual application of the cutting pressure which increases as the pencil passes along the blade resulting in a distribution and regulation of the cutting strains such as to enable the blade 85 to take these strains without breaking or buckling unduly. The shoulder B narrows gradually (to allow shavings to fall from the pencil) and supports the tip of the blade in the event of downward pressure upon the 90 pencil.

After the completion of the stroke the pencil is turned slightly in the fingers, and again drawn across the blade in a similar manner, and so on until the required point is obtained.

95 The shavings are neatly deposited below the blade. The length of point is varied at will by raising or lowering the hand holding the pencil.

Having now particularly described and ascertained the nature of my said invention and in what manner the same is to be performed, I declare that what I claim is:—

1. In a pencil sharpener, a base having a pair of longitudinal channels opening in one face of said base defining a mid rib and side edges, the latter extending above the level of said mid rib to form pencil guides, said mid rib being provided with means diagonally arranged for orienting a double edge wafer 105 110

blade diagonally with respect to said channels, and means for clamping said blade in place, said base being of such width that the wafer blade extends substantially across said channels.

- 5 2. In a pencil sharpener as claimed in claim 1, the channels tapering toward one end and being reversely arranged with respect to each other.
- 10 3. In a pencil sharpener, a base having a channel opening in one face thereof defining

a blade support on one side and a pencil guide on the other, said pencil guide being of greater elevation from the bottom of said channel than said blade support, means on said blade support for securing a blade diagonally, said base being of such width that said blade extends substantially across said channel. 15

In testimony whereof I have affixed my signature.

R. E. WRIGHT.
